LIGHTING DEVICE

Louis G. Boomsma, New York, N. Y.

Application June 17, 1939, Serial No. 279,602

1 Claim. (Cl. 176—126)

This application relates to lighting devices and more particularly to connectors, clips and sockets for these devices.

It is one object of my invention to provide a mounting for tubular lamps whereby the tube 5 may be changed as easily as an ordinary Edison base lamp.

It is another object of my invention to arrange a series of lamps of the tubular type, and having the bases insulated so as to avoid danger of 10 shock.

It is another object of my invention to allow easy replacement of one lamp in a series without disturbing the rest.

It is another object of my invention to provide 15 a coupling between tubes used in series to provide a good electrical connection, safe against shock, and yet without fixed parts.

It is another object of my invention to eliminate the necessity of complicated bases on lamps 20 of this type, and to provide instead a base which is easily used.

It is further an object of my invention to provide 25 clips for holding L tubes in either cove lighting systems or in ceiling lights, from which clips the tubes may be readily removed.

It is another object of my invention to provide 30 a series of lamps each short enough to handle easily in stock, shipment and replacement and mounted so as to give light effect of continuous tube.

It is further an object of my invention to permit 35 the replacement of tubes in either cove lights or ceiling lights without the use of tools.

In the past it has been inconvenient to use 40 high voltage long tubes in ordinary room lighting because of the insulating difficulties due to high voltage, and the necessity of having a skilled installation man replace defective or burnt out tubes. By employing the type of sockets and clips which I have described in this application, it is possible for anyone, without the use of tools 45 to replace any of the standard lights which I am proposing to use.

In the drawings:

Fig. 1 shows a lighting installation embodying 50 sockets and retaining clips in accordance with my invention;

Fig. 2 is an enlarged view of one form of socket which I may use to connect two L type tubes;

Fig. 3 is an enlarged view of an end socket for 55 an L tube;

Fig. 4 is a view of a retaining spring clip used to hold a tube in a socket such as shown in Figs. 1, 6 or 10;

Fig. 5 is another form of clip for a ceiling light; Fig. 6 is a fragmentary view of two straight tubes connected by a connector made in accordance with my invention;

Fig. 7 is a view of a straight tube with mushroom connectors in accordance with my invention;

Fig. 8 is an elevation view of a method of connecting all tubes to give the effect of a continuous tube;

Fig. 9 shows an end view of a trough installation made in accordance with my invention; and

Fig. 10 shows a top view of such an installation showing the common terminal at one end and the clips holding the intermediate tubes in place.

Referring first to Fig. 1, I have shown a lighting installation using both straight tubes 3, 3, and L type tubes 2, i. e., those having a straight portion and a short part at each end which is at right angles to the main portion of the tube, as the tube 2. As shown, the intermediate socket 4 has a single metal plate 9 and a single spring 8, and is free to assume any position to contact both tubes 2—2. The end sockets 5 are identical with the socket 4, excepting that they have but one outlet, and are connected to the supply circuit. The straight tube 3 is shown with an ordinary mushroom terminal 10 at one end, and a special terminal which incorporates a spring 8a at the other. This permits the use of a fixed length socket arrangement. The tube is inserted by merely compressing the spring 8a at the one end into the socket 6 and then allowing the other end to fit into its socket 7 partly releasing the spring 8 in so doing. It may be readily seen that the tube will fit tightly between the sockets 6 and 7, and will be continually urged into close contact with these sockets by the spring 8. It may also be seen that the 40 sockets instead of having the usual complicated spring arrangements need but be insulating cups with the metal disk contact in the bottom. It may be seen that not only is the construction greatly simplified, but also the problem of replacing tubes. Between sockets may be placed, instead of one tube as shown in Fig. 1, several tubes, and these tubes may be connected by a connector of the type 21 shown in Fig. 6. This connector provides a spring connection 16 insuring good contact, and requires no skill in connecting, and prevents anyone touching the tube while it is operating from getting an electrical shock.

In the above I have treated the series of tubes 55 3—3 as one. It is an advantage of the connec-
